(57) **CLAIM**

The ornamental design for a portable flashlight and device holder, as shown and described.

DESCRIPTION

FIG. 1 is a front top perspective view of a portable flashlight and device holder shown in a closed configuration.

FIG. 2 is a rear bottom perspective view of a portable flashlight and device holder.

FIG. 3 is a front elevational view of the portable flashlight and device holder shown in FIG. 1.

FIG. 4 is a rear elevational of the portable flashlight and device holder shown in FIG. 1.

FIG. 5 is a right side elevational view of the portable flashlight and device holder shown in FIG. 1.

FIG. 6 is a left side elevational view of the portable flashlight and device holder shown FIG. 1.

FIG. 7 is a top plan view of the portable flashlight and device holder shown in FIG. 1.

FIG. 8 is a bottom plan view of the portable flashlight and device holder shown in FIG. 1.

FIG. 9 is a front perspective of the portable flashlight and device holder showing the stand in an extended position.

FIG. 10 is a rear, right side perspective view of the portable flashlight and device holder shown in FIG. 9.

FIG. 11 is a right side elevational view the portable flashlight and device holder shown in FIG. 8; and,

FIG. 12 is rear perspective view of the portable electrical charger shown with the lower lid in an open configuration. The broken line showing of the electronic device in FIG. 12 is for environmental purposes only and forms no part of the claimed design.
